UNITED STATES PATENT OFFICE

2,500,685

TUBE CUTTER

John G. Johnston, Los Angeles, Calif.

Application February 12, 1948, Serial No. 7,793

1 Claim. (Cl. 164—60)

1

This invention relates to new and useful improvements and structural refinements in tube cutters, and the principal object of the invention is to provide a device of the character herein described, which may be conveniently and effectively employed for the cutting of tubes, pipes, rods, round bars, and the like.

A further object of the invention is to provide a tube cutter which is simple in construction, which may be easily and conveniently manipulated, and which will effectively cut the tube, or the like, without causing damage to the same.

Another object of the invention is to provide a tube cutter which will not easily become damaged, which will readily lend itself to economical manufacture, and which is otherwise well adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is a top plan view of the invention;

Figure 2 is a front elevational view thereof, and

Figure 3 is a cross sectional view, taken substantially in the plane of the line 3—3 in Figure 2.

Like characters of reference are employed to designate like parts in the specification and throughout the several views.

Referring now to the accompanying drawings in detail, the invention consists of a tube cutter designated generally by the reference character 10, the same embodying in its construction a suitable stand 11 including a pair of end pieces or legs 12 which are rigidly secured together at the upper end thereof by means of a substantially horizontal, inverted U-shaped channel 13.

This channel constitutes what will hereinafter be referred to as a bed, the same being adapted to rotatably receive the work, namely, a piece of tubular stock, indicated by the reference character 14.

The bed 13 is of elongated configuration, and a pair of projecting members 15 are secured to the mid portion of the bed as will be clearly apparent.

These members 15 in turn, carry a pair of axially aligned bearing blocks 16 in which a shaft 17 is rotatably journaled, the latter carrying a substantially cylindrical driving drum 19, the purpose of which will be hereinafter more fully described.

A pair of further leg members 20 are secured to the mid portion of the bed 13, the members 20

being similar to the aforementioned members 12, and a carrier 21 is pivotally attached as at 22 to the members 20, matters being so arranged that the carrier 21 is swingable upwardly and downwardly, as indicated at 23.

An electric motor 24 is mounted on the carrier 21, the armature 25 of this motor being provided with a pulley 26 which, in turn, is connected by a belt 27 to a relatively large pulley 28 secured to a shaft 29.

The shaft 29 is rotatably journaled in suitable bearing blocks 30 provided on the carrier 21, and also carries a drum 31, operatively connected by means of two or more belts 32 to the aforementioned drum 19.

It will be apparent from the foregoing that rotation of the motor armature 25 will produce rotation of the drum 19 at a relatively reduced rate of speed, and the weight of the pivoted carrier 21 will, of course, assure that the belts 32 are maintained in a taut position at all times, so as to eliminate the possibility of slipping.

An arm 33 is pivotally attached as at 34 to the leg members 20, the upper end of this arm carrying a rotatable cutter wheel 35, while the lower end of the arm is pivoted as at 36 to a link 37 which, in turn, is pivoted as at 38 to one arm 39 of a bell crank 40. This bell crank is fulcrumed as at 41 upon a shaft 42 provided on the leg members 20 and the remaining arm of the bell crank is configurated so as to provide what may be referred to as a foot pedal 43.

Matters are so arranged that when the invention is placed in use, downward pressure applied to the foot pedal 43 (in the direction of the arrow 44) will cause the rotatable cutter wheel 35 to press against the tube 14 which is to be cut (see arrow 45), this action urging the tube 14 in frictional contact with the periphery of the rotatable drum 19. Of course, the drum 19, by virtue of its rotation, will impart rotation to the tube 14 and also, to the cutter wheel 35, and as a result, the tube will be severed.

If desired, the drum 19 may be formed in the periphery thereof with annular grooves or channels adapted to receive the belt or belts 32, so that the tube 14 frictionally engages the actual periphery of the drum 19, rather than the belts 32, as shown in the accompanying drawings.

To assist and materially hasten the cutting operation, the bed may be formed with a suitable recess wherein a further cutter wheel 46 may be rotatably mounted on a suitable stub shaft 47 the wheel 46, of course, being disposed in the plane of the wheel 35, as will be readily under-

stood. Moreover, the bed 13 may be equipped with a plurality of sets of upstanding guide members 48, which will effectively facilitate the application of the work to the bed.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope 10 of the invention as claimed.

Having described the invention, what is claimed as new is:

In a tube cutter, the combination of a stand including a work-receiving bed, a rotatable drum 20 mounted on said stand at one side of said bed, a driven shaft supported by said stand, a pulley secured to said shaft, a combined work-engaging

and driving belt passing around said pulley and said drum, a movable cutting element disposed at the remaining side of said bed and urging the work in frictional engagement with said belt, and combined means for rotating said shaft and maintaining said belt in a taut condition, said means comprising an elongated and substantially horizontal supporting member pivoted at one end thereof to said stand and having said shaft journaled on its intermediate portion, and a motor mounted on the free end portion of said member and operatively connected to said shaft.

JOHN G. JOHNSTON.
